UNITED STATES PATENT OFFICE.

CHARLES G. CONN, OF ELKHART, INDIANA.

CORNET.

1,240,177.

Specification of Letters Patent. Patented Sept. 18, 1917.

Application filed October 8, 1914. Serial No. 865,690.

To all whom it may concern:

Be it known that I, CHARLES G. CONN, a citizen of the United States, residing at Elkhart, in the county of Elkhart and State 5 of Indiana, have invented certain new and useful Improvements in Cornets, of which the following is a specification.

The object of my invention is to avoid the short turns found in the wind passage 10 of cornets heretofore used and in so doing, produce an instrument which plays freer, better and more satisfactorily in every way and at the same time gives a greater volume of tone.

Another object of my invention is to place the tuning slide between the valves and rear end of the bell tube and in close proximity to the thumb of the operator's hand when in playing position, so that the 20 player may tune the instrument as he plays by turning the thumb screw which is connected to the tuning slide.

In the drawing:—

Figure 1 is a side elevation of a cornet 25 embodying my invention;

Fig. 2 is a similar view of a side of a cornet opposite to that shown in Fig. 1.

The reference numeral 1 designates a mouth pipe and 2 the valves of a cornet of 30 any approved construction. 3 designates the bell tube, or bell, the bore of which is of a gradual taper from end to end.

4 is a quick-change-to-A slide in the mouth pipe.

35 The principal tuning slide, as shown in the drawings, is positioned between the valves and the inner end of the bell 3, in an upright or perpendicular position. That is to say, the principal tuning slide is upright 40 or perpendicular to the main longitudinal lines of the cornet when the cornet is held in playing position.

The member 5 of the principal tuning slide is shown in the drawings as leading 45 from the first valve casing, but it is, of course, obvious that it may lead from either of the valve casings as found most desirable. This member is deflected downwardly and thence upwardly to a vertical or perpendicular position. 6 is another upright member of the main tuning slide which is 50 of greater diameter than the member 5 and

of a diameter equal to the inner end of the bell pipe. 7 is the sliding member of the main tuning slide, one leg of which is of a 55 diameter equal to the diameter of the member 5 while the other end is of a greater diameter and equal to the diameter of the member 6, from which it will be seen that the wind passage, commencing at the top 60 of the member 5 is of increasing diameter through the slide 7, member 6 and the bell pipe 3 which results in the instrument playing freer, better and more satisfactory and which enables me to get a greater volume 65 of tone out of the instrument.

I have shown in the drawing a bracket 8 secured between the members 5 and 6 of the tuning slide in which bracket is revolvably mounted a thumb nut provided with 70 interior screw threads while I have secured a stem 10 to the slide member 7, one end of the stem being secured to the slide member, the other end extending through the thumb nut 9 whereby the slide may be quickly and 75 evenly adjusted to make the instrument high or low in pitch.

The position of the principal tuning slide between the valves and the inner end of the bell eliminates the short turns in the wind 80 passage of cornets as heretofore constructed which now results in the instrument playing freer and giving better satisfaction and a greater volume of tone. In the old style of cornet, it was necessary to remove the 85 cornet from the player's lips in order to tune it, it often requiring several trials before the desired tone could be attained, whereas in my invention the player can tune his instrument while he is playing, by 90 simply moving his thumb over the knurled thumb screw 9, thereby not losing a single note of the composition.

I claim:—

1. A cornet having a tuning slide in the 95 form of an open-ended, vertically arranged loop, positioned between the first valve casing and the mouth piece, said loop comprising part of the tube connecting said casing and the bell tube; a thumb nut held against 100 axial movement and a coacting screw held against rotation positioned within the aforesaid loop for adjusting said tuning slide.

2. A cornet having a tuning slide in the

form of an open ended, vertically-arranged loop, positioned between the first valve-casing and the mouth piece, said loop comprising part of the tube connecting said casing and the ball tube; and means positioned within the aforesaid loop for adjusting said tubing slide.

The foregoing specification signed at Elkhart, Ind., this 17th day of September, 1914.

CHARLES G. CONN.
